US0D1079896S

(12) **United States Design Patent** (10) **Patent No.:** **US D1,079,896 S**
(45) **Date of Patent:** **** Jun. 17, 2025**

(54) **APPLICATOR MODULE**

- (71) Applicant: **NORDSON CORPORATION**,
Westlake, OH (US)
- (72) Inventors: **Thomas Burmester**, Bleckede (DE);
Sang Hyub Shin, Duluth, GA (US)
- (73) Assignee: **Nordson Corporation**, Westlake, OH
(US)
- (**) Term: **15 Years**
- (21) Appl. No.: **29/781,856**
- (22) Filed: **Apr. 30, 2021**
- (51) LOC (15) Cl. **23-01**
- (52) U.S. Cl.
USPC **D23/233; D15/144.2**
- (58) **Field of Classification Search**
USPC D23/213, 233–241, 244, 245, 246–249,
D23/321, 421; D15/7, 144.2; D24/129;

(57)

CLAIM

The ornamental design for an applicator module as shown and described.

DESCRIPTION

FIG. 1 is an isometric view of an applicator module according to a first embodiment;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of an applicator module according to a second embodiment;

FIG. 9 is a front elevation view thereof;

FIG. 10 is a back elevation view thereof;

FIG. 11 is a left side elevation view thereof;

FIG. 12 is a right side elevation view thereof;

FIG. 13 is a top plan view thereof; and,

FIG. 14 is a bottom plan view thereof;

The broken lines in FIGS. 1-14 are for the purposes of illustrating portions of the applicator module that form no part of the claimed design.

1 Claim, 14 Drawing Sheets
